UNITED STATES PATENT OFFICE

FRANCIS L. MCGARY, OF HARDINSBURG, KENTUCKY

COLLAPSIBLE CONTAINER

Application filed September 3, 1929. Serial No. 390,096.

This invention relates to collapsible barrels or hogsheads.

An object of the invention is the provision of a container constructed in such a manner that it may be economically manufactured, readily assembled or dismantled.

Another object of the invention is the provision of a container of the collapsible type which may be readily assembled or dismantled, the staves and heads being so constructed that they may be packed in neat bundles and shipped from the factory to the place where the containers are to be assembled, the battens of one head being spaced 10 relatively to the battens on the opposite head so that the battens of one head will fit between the battens of the other head in order to provide for packing the heads in compact bundles.

20 A further object of the invention is the provision of a container formed of staves and heads which may be readily assembled or disassembled with hoops disposed in vertical planes which are at angles to each other for 25 securely sealing the container or its contents against rupture.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure 35 from the salient features of the invention as expressed in the appended claims.

Figure 1 is a view in perspective of a container constructed in accordance with the principles of my invention.

40 Figure 2 is a sectional view in elevation of the container taken along the line 2—2 of Figure 3.

Figure 3 is a horizontal section taken along the line 3—3 of Figure 2.

45 Figure 4 is a view in perspective of one of the staves.

Figure 5 is a view in perspective of another form of the invention.

50 Figure 6 is a vertical section of the form shown in Figure 5.

Figure 7 is a view in elevation of the plurality of the staves formed into a compact bundle.

Figure 8 is an enlarged fragmentary view in perspective of a modified form of the stave.

Figure 9 is a vertical section taken along the line 9—9 of Figure 8.

Figure 10 is a view in perspective of the contents of the container shown in Figure 5 with the staves removed.

Referring more particularly to Figures 1—4 inclusive, 10 designates a top head constructed of boards formed in proper shape and secured together by spaced battens at 11. A bottom head 12 similarly constructed and provided with battens 13 spaced a less distance apart than the battens 11 so that the top and bottom heads may be placed in flat contact with each other when packed for shipment with the battens 13 disposed between the battens 11 and having their outer edges in close contact with the inner edges of the batten 11.

A plurality of staves 15 are similarly constructed and since they are of the same width, the staves are interchangeable so that in assembling a barrel no time will be lost in attempting to fit the staves to the heads. In this connection, it may be stated that the barrels have a circumference of either 150" or 144" as a matter of convenience in order to provide for equal width of the staves. Where 150" circumference is employed, 20 staves will be utilized each having a width of 7½" and in like manner where 25 staves are employed each stave will be 6" wide. When the barrel has a circumference of 144", 24 6" staves will be required or 32 4½" staves will be necessary. As a matter of fact where a 6" stave is employed, it may be used in the construction of either the 150" or 144" containers.

Each stave is formed with a flat upper end 16 and a lower end 17 having cleats 18 and 19 secured to the lower end of the stave in spaced parallel relation. Cleat 18 may be of less length than cleat 19 without affecting the spirit of the invention. A metal member 20 is bent around cleat 18, into a U-shaped member within the space between the cleats and then into an inverted U-shaped member 100

which embraces the cleat 19. This metal member prevents wear on the cleats.

As shown more particularly in Figure 2, the U-shaped portion 21 of the metal member 20 forms a socket to receive an edge of the bottom head 12. When the staves are assembled around the bottom head and a lower hoop 22 is forced on the bottom end of the staves, the staves will be held in secure relation to the bottom. Any number of hoops such as 23, 24 and 24a are applied along horizontal planes at spaced distances from the hoop 22. The container or hogshead is then packed with material and after it has been properly filled the top head 10 is then applied in position. The horizontally disposed hoops provide means for binding the staves against the peripheries of the heads.

A pair of hoops made of strips of sheet metal are disposed in vertical planes which are at an angle to each other and are brought around the top and bottom heads and over the vertical walls of the container in close association with the hoops located in the horizontal planes. These vertically disposed hoops 25 and 26 are drawn taut and are secured together with the ends of the metal strips being bound as at 27 at the top and bottom of the container.

30 By such a construction, a barrel is formed which is not only bound by horizontally disposed hoops but by hoops located in vertical planes which are approximately at right angles to each other. Where the barrels are subjected to severe strain, it may be desirable to bind the vertically disposed hoops together at points where they are closely adjacent the outer faces of the top and bottom heads. The vertically disposed hoops not only aid in maintaining the entire package such as the container intact but permit ready assembling or dismantling of the container.

Referring more particularly to Figures 45 5-10 inclusive, it will be seen that a modified form of the container is employed in which the bottom head is placed in a predetermined position and the staves 15a are assembled around the bottom with the groove in the inner faces of the staves receiving the periphery of the bottom. Hoops 40, 41, 42 and 43 are placed in position in their order thereby providing for the partial assembling of the barrel.

55 Endless bands 34 and 35 are inserted through the openings 37 in the bottom head 31 with said bands crossing each other at the central portion of the head 31 and with the bands engaging the outer faces of the battens 45. The free ends of the straps or bands 34 and 35 are disposed along the inner face of the barrel with the free ends of the bands being brought over the top of the barrel and bent downwardly over the outer face of the

The materials are packed into the barrel after which the top head 30 is applied in position while the upper ends of the straps or bands 34 and 35 pass through openings in the head 30. After the head 30 is in position, the free ends of the straps 34 are brought together and secured by clinching as at 36 with the ends of the straps 34 engaging the battens on the head. The free ends of the strap 35 are likewise brought together and clinched in the well known manner by securing the ends together.

By this construction, the contents 32 of the container 33 can be held as a separate unit within the container so that when the hoops 40, 41, 42 and 43 are removed it will permit the staves 13a to fall away from the barrel while the contents of the barrel are maintained in a compact bundle between the heads 30 and 31 by the straps 34 and 35.

85 A modified form of the cleat connected to the stave is shown in Figures 8 and 9. In this case a metal plate 50 is secured in any approved manner to the inner face at the lower end of the stave 51 after the plate has been punched to provide lugs 52 and 53. Pairs of lugs 52 and 53 are disposed in vertical alignment while the pairs 52 and 53 are shown in horizontal alignment. Nevertheless the space formed between the projecting edges 54 is provided to receive the edge or periphery of the bottom head 31.

90 The cleats 44 of a head 30 are spaced a greater distance apart than the cleats 45 of the head 31 so that when these heads are packed for shipment in close contact with each other the outer faces of the cleats will engage a face of the adjacently disposed head. These heads are then bound together in any approved manner and shipped in compact bundles.

95 As shown more particularly in Figure 7, the particular construction of the staves in either case permits the staves to be folded together in a neat compact bundle with the free end 16 of one stave abutting the metal member 20 adjacent the cleat 18 in pairs. These staves are then bound together by means of bands 60.

115 I claim:

1. A collapsible container comprising heads, a plurality of staves circumferentially disposed, hoops co-operating with the heads for retaining the staves in position and annular-hoops disposed in vertical planes for aiding in securing the heads in operative relation with respect to the contents of the container, one of the heads having passages to receive the vertically disposed hoops.

120 2. A collapsible container comprising heads, a plurality of staves circumferentially disposed, hoops co-operating with the heads for retaining the staves in position and annular hoops disposed in vertical planes aiding in securing the heads in co-operative re-

130

lation with respect to the contents of the container, the last-mentioned hoops and the heads forming with the contents of the container a unit, one of the heads having passages to receive the vertically disposed

5 hoops.

3. A collapsible container comprising heads, a plurality of staves circumferentially disposed, hoops co-operating with the heads for retaining the staves in position and annular hoops for aiding in securing the heads in co-operative contact relation with respect to the contents of the container, each stave having one end provided with metal plates

10 having spaced lugs adapted to engage opposite faces of a head, said lugs projecting from the plates and formed integrally therewith, the lug being connected at all points except the free edge which engages the opposite

15 faces of the heads.

CERTIFICATE OF CORRECTION.

Patent No. 1,839,111.

Granted December 29, 1931, to

FRANCIS L. McGARY.

It is hereby certified that error appears in the printed specification of the above numbered patent requiring correction as follows: Page 3, after line 6, insert the following as claim 3:-

3. A collapsible container comprising heads, a plurality of staves circumferentially disposed, hoops cooperating with the heads for retaining the staves in position, and annular hoops disposed in vertical planes for aiding in securing the heads in operative relation with respect to the contents of the container, with the greater portions of the vertically disposed hoops being in contact with the outer surface of the contents of the container, the heads, vertically disposed hoops, and the contents forming a unit.

Same page, line 7, for claim number "3" read 4; and that the said Letters Patent should be read with these corrections therein that the same may conform to the record of the case in the Patent Office.

Signed and sealed this 21st day of June, A. D. 1932.
